(57) **CLAIM**

We claim the ornamental design for an inflatable water slide, as shown and described.

DESCRIPTION

FIG. 1 illustrates a right lateral perspective view of an inflatable water slide showing our new design;

FIG. 2 illustrates a right plan view showing our new design;

FIG. 3 illustrates a left plan view of our new design;

FIG. 4 illustrates a front plan view of our new design;

FIG. 5 illustrates a rear plan view of our new design; and,

FIG. 6 illustrates a top elevational view of our new design.

The broken lines of FIGS. 1-6 are for illustrative purposes only and form no part of the claimed design.
